HORSESHOE PITCHING STAKES AND KIT
THEREFOR

Henry St. Pierre, Worcester, Mass.

Application April 10, 1950, Serial No. 154,955

3 Claims. (Cl. 206—47)

1

This invention relates to a new and improved horseshoe pitching stake and an improved container therefor, forming a kit for two pairs of horseshoes and two stakes, for great convenience in carrying the set and economy of manufacture.

The principal object of the present invention is to provide a kit for a set of horseshoes and stakes which is easily carried in a convenient manner and which takes up a minimum amount of space; the provision of a kit as above stated including a pair of stakes each of which is formed in two separate parts, one part embodying a ground-penetrating point at one end and a socket at the other end, the socket being of a size to receive the other part of the stake which has a diameter similar to the first part, said socket having a hole and said second stake part likewise having a hole for the reception of a pin to secure the parts together in a kind of telescoping relation to form a horseshoe pitching stake of required length, but in fact made of two parts of substantially equal length, each of said parts having length comparable to the combined widths of a pair of regulation horseshoes.

Another object of the invention resides in the provision of a pair of horseshoe stakes as above described adapted to be assembled in kit form in a box or container, the latter being of a length to just accommodate a pair of shoes in side by side relation so that the stake parts may be put in the box therewith and be co-extensive in length with the box and with the combined widths of the two pairs of horseshoes in the relation stated.

Other objects and advantages of the invention will appear hereinafter.

Reference is to be had to the accompanying drawings in which

Fig. 1 is a plan view of a horseshoe pitching kit according to one form of the invention, showing the kit open;

Fig. 2 is a view illustrating how the kit of Fig. 1 is carried and its comparative size to the human figure;

Fig. 3 is a perspective view of the kit showing the same closed and illustrating the relative proportions thereof;

Fig. 4 is a view illustrating a novel horseshoe pitching stake assembled;

Fig. 5 is an enlarged section through the joint of the novel two-part horseshoe pitching stake;

Fig. 6 is a perspective view of a different kind of kit for the same purpose;

Fig. 7 shows a modified two-part stake, parts being broken away and in section; and

Fig. 8 is a view similar to Fig. 2 but showing how the kit of Fig. 6 may be carried.

Horseshoe pitching sets including two pairs of horseshoes and two stakes of required length are commonly packaged in a box which obviously has a length long enough to accommodate the stakes

2

which are from 25 to 30 inches long. This makes a very unwieldy package because it is long, flat and relatively narrow and, of course, the horseshoes and stakes are heavy. The present invention, however, accommodates two pairs of regulation horseshoes in a box just 14 inches long at its inside longest dimension, two pair of regulation horseshoes when packed together requiring a length of 14 inches; and the present novel stakes are divided in the middle in two parts, each of which is 14 inches long, but because one part has a socket into which an end of the other part telescopes, the present stakes when assembled are between 26 and 27 inches long.

In other words, the kit of the present invention is exactly as long as required by two side by side pairs of regulation horseshoes nested, and the stake parts are exactly the same length and fit within the same box. This box may be relatively flat, i. e., about 2½ inches high, 14½ inches long and 7 or 8 inches wide. Such a box or kit may be carried under the arm in a manner of a briefcase, see Fig. 2, in a very convenient and comfortable manner. On the other hand, boxes of the prior art, being 25 to 30 inches long or more are, of course, unwieldy and hard to carry because of the odd elongated shape and weight.

Referring first to Fig. 1, there is shown a box having a cover 10, ends 12, front wall 14, rear wall 16 and a conventional bottom. The two pairs of horseshoes in nested relation are indicated at 18 and the stakes in two parts are indicated at 20 and 22. It will be seen that the box is exactly long and wide enough for the two pairs of nested horseshoes and the stake parts 20 and 22 are just long enough to fit in the box lengthwise. The box being but a little longer than 14 inches, it may be carried in a manner of a briefcase by the figure 24 as seen in Fig. 2. Thus the case is convenient and easily balanced in the hand as compared to cases 25 to 30 inches long.

The horseshoes themselves may be of any desired kind but are preferably regulation. Each stake part 22 is provided with a ground-penetrating point 24 at one end and a socket 26 at the other end. This socket receives an end of the stake part 20 which has a diameter similar to that of the part 22, the socket 26 therefore being enlarged. The socket 26 is provided with a pair of aligning holes 28 to align with the hole 30 in the stake part 20 for the reception of a cotter pin or the like 32, holding the telescoping parts of the stake parts together.

The lines 34 indicate the preferred ground line and when the stake parts are assembled, the same may be driven into the ground about the level of the socket 26 which helps in maintaining the stake in upright position, see Fig. 4 wherein the ground level is at 36.

However, when it is desired to pull up stakes,

3

this is easily done, the stake parts taken apart and returned to the kit with the horseshoes and the player's shoes, etc.

Another form of pitching stake is shown in Fig. 7 wherein the lower end of the upper stake part 38 is circumferentially grooved as at 40 just above a circumferential bevel 42. The socket 44 of lower stake part 46 is provided with a hole receiving a bevel end snap pin 48 mounted at the free end of a spring strip 50 secured only 10 at its end 52 to the lower stake part below the socket.

This construction allows the upper part 38 merely to be inserted in the socket, and the bevel 42 will cause the beveled pin 48 to retreat sufficiently to allow the upper stake part to seat, or substantially seat, in the socket, the pin 48 snapping back due to spring 50 to lock into the groove 40, regardless of the relative angularity of the 20 stake parts. This avoids the necessity of aligning the holes 28 and 30 in the respective stake parts as shown in Fig. 5.

Fig. 6 illustrates a container having a bottom part 54 to receive the shoes and stakes as in Fig. 1, and a hinged cover member 56. This box may be provided with snap catches 58 and a pivot suitcase handle 60, so that the kit may be carried by hand, as a suitcase, if desired, see Fig. 8, as well as being carried under the arm as in Fig. 2. The container of Fig. 6 may be of sheet metal or other suitable material and it will hold the shoes and stakes exactly as in Fig. 1, and will be of the same or very similar dimensions as the container of Fig. 1.

Having thus described my invention and the advantages thereof, I do not wish to be limited to the details herein disclosed otherwise than as set forth in the claims, but what I claim is:

1. A kit for a horseshoe pitching set comprising a container having a length substantially equal to the width of a pair of pitching horseshoes in side by side relation in the container, a pair of stakes each of which is composed of two substantially equal length parts, each part being substantially as long as the length of the container and lying lengthwise therein, a pair of said horseshoes in side by side relation in the container, and means to detachably secure the stake parts together in elongated form for use, said means including a socket on one member and an end on the other member selectively receivable therein, the socketed member being pointed, and the socket thereon being arranged longitudinally of the axis of the member on which it is located.

2. A kit for a horseshoe pitching set comprising a container having a length substantially equal to the width of a pair of pitching horseshoes in side by side relation in the container, a pair of stakes each of which is composed of two substantially equal length parts, each part being substantially as long as the length of the container and lying lengthwise therein, a pair of said horseshoes in side by side relation in the container, and means to detachably secure the stake parts together in elongated form for use, said container being relatively flat and having a handle on a narrow edge thereof.

3. A kit for a horseshoe pitching set comprising a container having a length substantially equal to the width of a pair of pitching horseshoes in side by side relation in the container, a pair of stakes each of which is composed of two substantially equal length parts, each part being substantially as long as the length of the container and lying lengthwise therein, a pair of said horseshoes in side by side relation in the container, and means to detachably secure the stake parts together in elongated form for use, said container being flat and narrow, a cover for the container, said cover being openable to expose a wide side thereof, said horseshoes in side by side relation taking up an area approximately equal to the area of said wide container side and of the cover, and being fully exposed upon opening the cover.
